UNITED STATES PATENT OFFICE

2,584,255

MERCHANTISING AND DISPLAY STAND

Alexander R. Brown, Portage la Prairie,
Manitoba, Canada

Application June 21, 1947, Serial No. 756,214

1 Claim. (Cl. 211—169)

1

My invention relates to improvements in merchandising and display stands, a primary object being to provide a device of the character hereinabove described upon which merchandise, and particularly merchandise of thin dimensions such as engine gaskets, piston rings and the like may be conveniently mounted either for storage or display or both with the advantage of ready visual reference as to size, type and the like.

A further object of my invention is to provide 10 a device of the character hereinabove described and for the purpose intended which is compact, bodily transportable, and of inexpensive construction.

With the foregoing objects in view, and such 15 other objects and advantages as will become apparent to those skilled in the art to which this invention relates as this specification proceeds, my invention consists essentially in the arrangement and construction of parts all as herein-after more particularly described, reference being had to the accompanying drawing which is a perspective representation of my merchandising and display stand with certain parts shown in fragmentary form.

My invention consists of a supporting structure collectively designated 1 and embodying a rectangular base 2 mounted upon casters 3, and a framework collectively designated 4 which consists of a pair of rear vertical components 5 and a front component 6.

The rear components 5 are united by the horizontal members 7, 8 and 9 and the front component 6 is united to each of the components 5 by means of the converging members 10 and 11.

Thus it will be seen that viewed in plan my framework 4 is triangular, but when viewed obliquely in elevation consists of a vertically rectangular frame formed of the members 5, 6, 10 and 11 and when viewed three dimensionally the said framework is seen to be of elongated wedge-shaped configuration wherein the component 6 represents the apex, and the components 5 the base.

Extending in a horizontally diagonal direction between the components 5 and 6 are stepped upper and lower stringers 12, to the corners of each step of which hinges 13 are secured. Each pair of vertically aligned hinges carries one of a plurality of vertically disposed frames 14 each surrounding and supporting a merchandise carrying and display panel 15. It will clearly be seen that the adjacent panels are spaced apart to the extent of twice the overhang on either side of each frame, and thus I provide means between the panels for sustaining them in spaced relationship at least equivalent to the

projectional extent of the merchandise which will be hung therefrom by means of hooks or the like.

When the set of panels on either side of the 5 central and frontal component 6 is closed it will be seen that the outer vertical edges 17 of my frames 14 lie in a common vertical plane, and both sets may be locked in such closed position by any convenient means such as the hooked locking bars 18 which are engageable with studs 19 at either end of the horizontal component 8.

Since various modifications can be made in my invention as hereinabove described and many apparently widely different embodiments of same made within the scope of the claims without departing from such spirit and scope, it is intended that all matter contained in the accompanying specification shall be interpreted as illustrative only and not in a limiting sense 20 and I desire only such limitations placed thereon as are specifically expressed in the accompanying claim.

What I claim as my invention is:

A merchandising and display stand comprising 25 in combination, a supporting structure embodying a base and a framework, said framework including vertical anterior and posterior components, two pairs of stepped, horizontal hinge stringers, each pair comprising at least 30 two of said stringers arranged in spaced, parallel, vertical, co-planar relationship with their ends in vertical alignment, said pairs diverging from said anterior component toward said posterior components, frames containing merchandise-holding panels hingedly secured to said stringers in overlapping relationship by the vertical edges thereof the other vertical edges of said frames lying in a common vertical plane at right angles to the plane of the anterior component when said frames are parallel with the common plane of the posterior components of said framework.

ALEXANDER R. BROWN.
